DENSITOMETER

Sebastian S. Matilla, Forest Hills, N.Y., assignor to Sperry
Rand Corporation, New York, N.Y., a corporation of
Delaware

Filed Dec. 11, 1963, Ser. No. 77,760

Term of patent 14 years

(Cl. D52—6)

FIG. 1.

FIG. 2.

FIG. 3

FIG. 1 is a front perspective view of a densitometer embodying my new design;

FIG. 2 is a rear perspective view thereof; and

FIG. 3 is a fragmentary sectional view taken along the line 3—3 of FIG. 1.

The dominant features of my new design are shown in solid lines in the drawing.

I claim:

The ornamental design for a densitometer, substantially as shown and described.
